DESIGN.

F. W. HENSON.

HOOD FABRIC.

No. 17,441.

Patented July 12, 1887.

UNITED STATES PATENT OFFICE.

FRANCIS W. HENSON, OF PHILADELPHIA, PENNSYLVANIA.

DESIGN FOR HOOD FABRIC.

SPECIFICATION forming part of Design No. 17,441, dated July 12, 1887.

Application filed December 31, 1886. Serial No. 222,228. Term of patent 7 years.

To all whom it may concern:

Be it known that I, FRANCIS W. HENSON, a citizen of the United States, residing in Philadelphia, Pennsylvania, have invented a new and original Design for Fabric for Hoods, of which the following is a specification.

My design for a knitted fabric for hoods is fully shown in the accompanying photographic illustration.

- 10 To The invention consists, essentially, of the design for a knitted fabric having on the body thereof undulating flounces overlying each other, the overlying edges having corresponding scallops.
- 15 In the complete hood illustrated the body of the hood is shown as having this design of

the fabric, as also has the cape P, while the front of the hood has any usual form of ruching, B.

I claim—

20 The design for a knitted fabric for hoods, having overlying undulating flounces, the edges of the flounces having scalloped outlines, substantially as shown and described.

In testimony whereof I have signed my name 25 to this specification in the presence of two subscribing witnesses.

FRANCIS W. HENSON.

Witnesses:

WILLIAM D. CONNER,
HARRY SMITH.
